UNITED STATES PATENT OFFICE.

JAMES M. GRAHAM, OF ATLANTA, GEORGIA.

FRACTURE FRAME.

Application filed May 9, 1923. Serial No. 637,739.

To all whom it may concern:

Be it known that I, JAMES M. GRAHAM, a citizen of the United States, residing at Atlanta, in the county of Fulton and State of Georgia, have invented certain new and useful Improvements in Fracture Frames, of which the following is a specification.

This invention relates to surgical appliances, and more particularly to extensible splints or fracture frames, for use in connection with the lower limbs, and has for one of its objects to provide a frame capable of adjustment to render it available for both limbs, the device involving certain novel features of construction, which adapt it to fit the conformation of the pelvic girdle in a manner conducive to effecting maximum comfort for the wearer.

A further object of the invention is the provision of improved means in a device of the class described, for firmly holding the fractured leg and thigh in a manner to be arbitrarily extended to any desired degree, and be conveniently accessible for examination and dressing purposes.

Other objects and advantages will be pointed out as this specification progresses, the invention consisting in the construction, combination, and arrangement of parts hereinafter described and claimed.

In the accompanying drawings forming part of this specification:

Figure 1 is a perspective view of a fracture frame embodying my invention, the foot receiving shoe not being shown.

Figure 2 is a side elevation of the lower portion of Figure 1, showing the foot and ankle support or shoe attached thereto.

Figure 3 is a perspective view of the under side of Figure 2.

Figure 4 is a perspective view of the shoe removed from the frame.

Figure 5 is a plan view of the hip engaging ring.

Figure 6 is a front elevation of the upper portion of Figure 1.

Figure 7 is a side elevation of Figure 6 looking in the direction indicated by the arrow.

Figure 8 is a top view of Figure 6.

Figure 9 is a sectional view on line 9—9 of Figure 6, the turnbuckles being omitted.

Figure 10 is a sectional view on line 10—10 of Figure 1.

Figure 11 is a sectional view on line 11—11 of Figure 1; and

Figure 12 is a rear view of a torso showing in dotted lines the normal position of the hip pad.

Referring to Figure 1 of the drawings, my improved fracture frame comprises a lower unitary frame section generally designated by the number 1, and an upper composite frame section 2.

The lower frame section comprises three upwardly extending, slightly diverging struts or lower frame members 3, 4, and 5, joined together intermediate their ends by a horse shoe shaped brace 6. The members 3 and 4 are preferably integrally joined together by a horizontally disposed cross bar 7, across the top of which extends at right angles a dovetail shaped spline 8. The spline is flat and preferably of uniform width and thickness and has downwardly and inwardly sloping sides, and is preferably welded to the cross bar at a point short of its free end, and extends rearwardly to the member 5, and is preferably an integral part thereof. A pair of vertically directed bolt holes 8' perforate the spline.

The upper extremity of each of the members 3, 4, and 5, is formed with right hand screw threads 6', upon each of which is threaded a turnbuckle 10. Extending respectively in straight alignment with the members 3, 4, and 5 are the extension rods or members 11, 12, and 13, which form a part of the frame section 2, each formed at its lower end with left hand screw threads 14, 90 and at its upper end with right hand screw threads 15. The lower ends of the rods have threaded engagement respectively with the turnbuckles 10, so that a turning movement of the turnbuckles to the right will bodily project their respective rods lengthwise upward, thus increasing the length of the fracture frame. The rod members 11, 12, and 13, with their respective turnbuckles in connection respectively with the members 3, 4, and 5, form what may be termed three straight extensible struts.

Removably threaded, one on the upper end of each of the rods 11 and 12, is a bifurcated terminal member or fitting 16, each fitted with a pivot pin 17 extending at right angles to and axially intersecting the axis of its respective rod. The inner opposite faces 18 of the bifurcation of each terminal member are preferably convexed and adapted to receive between them a lug 19 through which the pin 17 loosely extends to permit the

members 16 to swing to a slight degree at right angles to the plane of the lug, as indicated by dotted lines at 20.

The upwardly diverging rod 13 has threaded engagement with a bifurcated terminal member 21, the bifurcation thereof being formed by oppositely disposed vertical ears 25', and being adapted to slidably receive a relatively wide, thin lug 22, the latter being formed with a curved slotted opening 23, extending concentrically about the center point 24. A screw bolt 25 extends freely through one of the ears 25' and through said slotted opening and has threaded engagement in the opposite ear 25', whereby, when the screw bolt is firmly driven home, the lug 22 may be firmly clamped in the desired position. The planes of the lugs 19 and 22 are parallel, that of the latter extending vertically and transversely at right angles to the spline 8.

The lugs 19 and 22 are preferably an integral part of a ring 26, the former being disposed symmetrically about the line 27 extending at right angles to the lug 22, as shown in Figure 5. The extension members 11 and 12 are of different lengths, as is clearly shown in Figure 1, the variations being such as to place the ring in a plane disposed at an angle which inclines from the rear extension member 13 forwardly, and from the extension member 12 laterally, as is best illustrated in Figure 6 of the drawings, wherein the axis designated by the numerals 28-28 (Figure 8) is inclined to the left, while the axis 27-27 is inclined to the right. Inasmuch as the lugs 19 and 22 are disposed symmetrically about the axis 27-27 of the ring, and inasmuch as the slotted opening 23 of the lug 22 is concentric with the point 24 (which point is coincident with both axes 27-27 and 28-28), it is obvious that the ring may be oscillated about the center 24 to move the axis 28-28 to the position designated by the line 28'-28' (to which position the ring may be adjusted when the splint is to be used for the left leg), without changing the lateral distance between the pivot openings 17' and the vertical axis 29-29 of the frame. The openings 17', therefore, remain, to a very close approximation, in alignment, respectively, with the extension members 11 and 12, regardless of whether the ring is adjusted for the right or left leg, thus enabling the members 11 and 12 to be interchanged.

As stated in the foregoing, it is essential that the ring oscillate about the point 24, as distinguished from oscillating about the pivot 25, in which latter case, the ring would be bodily swung to the right or left beyond either of the members 11 or 12, the pivots 17 thus being thrown widely out of alignment with said members.

Owing to the forward and lateral inclina-

tion of the ring with respect to the vertical axis 29-29 of the frame, the member 12 will assume a position slightly in advance of the member 11, as shown in Figure 7 of the drawings. This is the result of oscillating the ring about the inclined axis 27-27 (Figure 7), in which movement one of the lugs 19 is thrown upwardly and rearwardly, and the other downwardly and forwardly, as indicated in Figure 8 of the drawings. The lugs 19 are thus thrown respectively slightly out of vertical alignment with the members 11 and 12, but to a negligible degree, as shown by the line 30-30 in Figure 8. As the members 11 and 12 are relatively thin and slender they will spring sufficiently without making any perceptible difference in the energy required to turn them. Obviously, the ring has bodily swung, as indicated in Figure 8, slightly to the left about the member 13 (which turns in the turnbuckles) to place the lugs in offset relation with respect to the line 30-30.

For the purpose of clamping the foot to the lower section of the frame, I provide a suitable shoe 32, having preferably a metallic sole 33, on the under side of which are a pair of spaced, longitudinally disposed lugs 34, having their adjacent faces properly inclined to slidably receive the spline 8. The sole has suitably threaded bolt holes adapted to receive screw bolts 34' (Figure 2), which latter extend loosely through the openings 8' of the spline. The shoe is thus removably secured to the frame in vertical alignment with the brace member 6, the means for securing the foot including an ankle strap 35 which is projected through a link 36 to form a loop through which latter the frame member 5 extends. The strap is adapted to be buckled around the leg, as shown in Figure 2, to restrict its forward movement. An instep strap 37 and a toe strap 38 serve to firmly strap the foot to the sole of the shoe 33. The shoe is preferably formed with overlapping flaps 38' and 38'' to render it available for several sizes of feet. Referring to Figure 12, wherein is shown the pelvic girdle of a torso, 39 designates the crest or highest point of the convex gluteus maximus muscle or buttock, while 40 designates a laterally directed crease at the base thereof. I have found that great comfort is extended the wearer by having the ring cross the rear of the thigh in an outwardly and upwardly direction at the base of the buttock, or, in other words, approximately in the direction of the crease. Further, the ring is tilted to cross the front of the thigh at a point higher up on the body than the crease 40, to more clearly conform to the furrow indicated at 41, which latter is formed at the juncture of the thigh with the abdominal wall. The ring is suitably padded, throughout its cir-

circumference, a section of which is shown at 42, and may be termed an obliquely positioned hip pad.

In operation, the limb is projected through the ring and the foot firmly strapped in the shoe. The fracture may now be brought into proper healing alignment by adjusting the turnbuckles, it being understood that the hip pad abuts against the trunk of the body, while the struts are extended. When it is desired to adjust the frame for use on the left leg, the numbers 11 and 12 are disengaged from the turnbuckles and terminal members 16, and interchanged, the screw 25 having been previously loosened to permit the lug 22 to slide in the member 21.

I claim:

1. In a device of the class described, comprising a frame extending from the region of the pelvis to and across the sole of the foot, means for releasably attaching the foot to said frame, means for arbitrarily extending said frame, including two removably attached extension rods of different lengths located at the front of the frame and a shorter rod spaced rearwardly therefrom and located midway therebetween, a ring adapted to receive the thigh of the leg and abut against the trunk of the body, a laterally slideable pivotal connection between said ring and said shorter rod, and a detachable connection between each of said extension rods and said ring whereby said extension rods may be detached and interchanged.

2. In combination with a fracture frame comprised in part of a plurality of similarly constructed upwardly diverging detachable struts disposed to form front and rear frame members, the free upper ends thereof terminating at different levels at points in close proximity to the juncture of the leg with the trunk of the body; of a ring surrounding the leg at said juncture, detachable similarly constructed connections between the front struts and said ring, and a laterally slideable pivoted connection between said ring and said rear frame member.

3. In combination with a fracture frame comprised in part of a plurality of upwardly diverging detachable struts forming front and rear frame members terminating at their free upper ends at different levels at points located in close proximity to the juncture of the leg with the trunk of the body; a ring surrounding the leg at said juncture, and connections, including detachable connections, between said ring and said struts constructed in a manner to enable the ring to be oscillated bodily about a point coincident with its center, when detached from said detachable connections.

4. In a fracture frame adapted to receive the leg and having a hip pad adapted to engage with the trunk of the body and including means constructed and located in a manner to enable the frame to be extended when the same is attached to the leg, said frame being constructed with an open, unobstructed front, and a foot receiving shoe insertable through said opening front and including strap members whereby the foot may be strapped firmly in the shoe, a dovetailed spline forming part of the frame extending longitudinally of the front when the frame is positioned on the leg, and a slide-way formed on the sole of the shoe adapted to slidably receive said spline.

5. In a fracture frame for legs, having a shoe adapted to releasably hold the foot, a ring adapted to surround the leg and engage with the trunk of the body, and extensible front and rear struts between said shoe and ring, the upper portion of said struts being detachably connected to said ring and frame, the detachable connections of said front struts including lugs disposed in parallelism on said ring at an acute angle to the plane thereof and disposed symmetrically about an axis intersecting the center thereof, and bifurcated members, one for each of the front struts, adapted to receive said lugs, the inner faces of the bifurcation being of concave formation, for the purpose set forth.

In testimony whereof I affix my signature.
JAMES M. GRAHAM.
